UNITED STATES PATENT OFFICE.

MORRIS S. WRIGHT, OF WORCESTER, MASSACHUSETTS, ASSIGNOR TO
REGINALD FRY, OF MORRISTOWN, NEW JERSEY.

REED-ORGAN.

SPECIFICATION forming part of Letters Patent No. 380,071, dated March 27, 1888.

Application filed July 27, 1887. Serial No. 245,396. (No model.)

To all whom it may concern:

Be it known that I, MORRIS S. WRIGHT, of the city and county of Worcester, and Commonwealth of Massachusetts, have invented 5 new and useful Improvements in Reed-Organs; and I do hereby declare that the following is a full and clear description of the same, reference being had to the accompanying drawings and letters of reference marked thereon, forming 10 a part of this specification, and in which—

Figure 1 represents, on line *a a*, Fig. 2, looking in the direction indicated by arrow 1, a vertical section through one set of reed-chambers, air-chambers, and qualifying-tubes, the 15 air-valve over the line of section in Fig. 2 being removed to show the valve-seats and the form of the air-openings, all as will be herein-after more fully described; and Fig. 2 represents a cross-section, on line *b b*, Fig. 1, looking 20 in the direction indicated by arrow 2, of so much of a reed-organ as is necessary to illustrate my present invention, as will be herein-after described.

To enable those skilled in the art to which 25 my invention belongs to make and use the same, I will proceed to describe the invention more in detail.

The nature of my invention consists in improvements in reed-organs, viz: first, in the peculiar construction and combination of the various rigid parts of the instrument and usually 30 called the "reed-pan," as will be herein-after described; second, in the combination and arrangement, in a reed-organ, of a series of air-chambers, a series of qualifying-tubes, and a 35 series of hinged stops, all relatively arranged in relation to each other as will be herein-after more fully described; third, in the combination, with the three communicating air-chambers, and the air-chambers of the reeds above 40 the same, and a single qualifying-pipe, of a stationary cut-off interposed or arranged between the lower communicating air-chambers and the reed-chambers above the same, as will 45 be herein-after described; fourth, in the combination and relative arrangement, in a reed-organ, of a peculiarly-constructed reed-pan, the same having its induction air-ports and air-valves and mechanism for operating the 50 same located and arranged in the large air-

chest at the back of the reed-pan, while a series of openings are arranged in the front of the reed-pan between a series of qualifying-tubes for the insertion and removal of the reeds at the front of the organ, all as will be 55 herein-after described; fifth, in the combination, with the induction air passages or ports of a given series of reeds arranged one above the other, of a perpendicular pendulum air-valve, as will be herein-after more fully described; 60 sixth, in the combination, with a pendulum air-valve for a series of air-induction ports, of recessed seats and communicating ports, as will be herein-after described; seventh, in the combination, with a pendulum-valve suspended 65 from a top pin, of lower guide-pins, one on each side, an operating-spring, and buffer in the rear, as will be herein-after described; eighth, in the combination, with the lower end 70 of the pendulum-valve, of an adjustable screw-stemmed metal eye, as will be herein-after described; ninth, in the combination, with the operating screw-stemmed metal eye and its valve, of a padded bell-crank and rod for operating the valve from the key-board, as will 75 be herein-after described; tenth, in the combination, in a reed-organ, of a series of reeds arranged one above the other and located in respect to their respective air-chambers as described, a series of horizontal qualifying- 80 tubes extending from the front of the air-chambers toward the front of the organ, with horizontal open spaces between them for the passage of the reeds, air-exit openings at the front of the qualifying-tubes, and a series of 85 hinged stops, all as will be herein-after described; eleventh, in the combination, in a reed-organ, with a series of reed air-chambers, relatively arranged as shown and described, and a series of reeds, one only to each set of air-chambers, and a series of openings in the front 90 of the reed-pan for the insertion of the reeds from the front of the organ in horizontal positions, of a series of plug-pieces fastened to the front of the reed-pan, and a series of qualifying-tubes secured to the front ends of the air-chambers and extending horizontally to the front of the organ, with horizontal open 95 spaces between them, all as will be herein-after more fully described.

My present invention relates to certain specified improvements, as will be hereinafter fully described, and I have therefore only shown so much of a reed-organ as is necessary to illustrate my invention, and the description will be confined mainly to the parts shown. The key-board, keys and their connections, stop-operating devices, casing, and proper means for supporting the instrument at the desired height may all be of ordinary construction.

In the drawings, the parts marked A constitute the lower or first tube or cell board, and which board runs from end to end and is made from a single piece of wood. The parts A' constitute the next or second section of tube or cell boards, and in this section are arranged the first series of reeds d. Section A' is made from a single piece of wood, and its front upper corner is cut out to receive the plug-piece B, which is made in a single piece and runs from end to end of the reed-pan.

B' is a dividing-board, which runs its full length and thickness between the part A' and the next or third tube or cell section C, made like the one A' below it.

C' is the plug-piece, and C'' is the next dividing-board, which also runs its full length and width between section C and next or fourth tube or cell section, D, D' being the plug-piece for this section and D'' the dividing-board between section D and the next or fifth tube or cell section, E, E' being the plug-piece and E'' the top board, as in this instance section E is the last one.

It will be understood that any desired number of tube or cell sections may be used—one above the other—and one great advantage of my mode of making and uniting the parts of the reed-pan is, that it enables the manufacturer to keep his stock all prepared, ready to be glued and fastened together in sections, as above described, whereby he can quickly put up any desired size of reed-organ from such prepared material and at short notice. Then, again, when the structure above described, and which I call the "reed-pan," is made up from separate pieces running from end to end of the structure, there is not that liability of the parts to warp and spring out of line or out of their proper relative positions, as in reed-organ structures as heretofore constructed.

It will be observed that the air-chambers proper—viz., F G H I J K L M—are all cut or cored out of the pieces A, A', C, D, and E. The side walls of air-chamber F are connected by the uncut parts 3 3, those of air-chamber G by the parts 4 4, those of air-chamber H by the uncut parts 5 5, those of air-chamber I by the uncut parts 5 5, those of air-chamber J by the uncut parts 6 6, those of air-chamber K by the uncut parts 6 6, and those of the air-chambers L and M by the uncut parts 7 and 7; and in addition to such natural-wood connections the parts are furthermore connected by the dividing-boards B', C', and D'', and reed-plugging pieces B, C', D', and E', and shade-piece E, and which parts extend the entire length of

the reed-pan, so that when said parts are all glued and fastened together there is scarcely a possibility of the least change in the parts, even when the instrument is placed in a very unfavorable position as respects dampness of room or atmosphere, and those skilled in the art to which my invention belongs will appreciate the results thus attained, since they tend greatly to the perfection of the class of instruments to which my reed-organ belongs.

Qualifying tubes or pipes N are connected to the front ends of the air-chambers, one to each reed and reed-chamber, with the exception that I, for three lower sections of three reeds each, employ but one large qualifying pipe, which occupies the space of three ordinary qualifying pipes. Each qualifying pipe has an opening, N', of the desired size to admit of the escape or exit of the air, and each of said openings is provided with a hinged stop, N'', and, if preferred, the stop may consist of a single hinged piece extending the length of the organ, so that one whole series of openings may be closed and opened by one motion of the player from the front of the organ.

I prefer to have each section or stop-piece arranged to be closed by a spring. As the stops are all arranged on the outside or front ends of the qualifying pipes or tubes, they always work easily and freely and close tightly. They never stick or bind in damp weather, nor are they loose in dry weather; consequently the action of the instrument in this respect can always be relied upon. Then, again, the stops being arranged at the front or air-exit ends of the qualifying tubes or pipes, thus bringing the latter between the stops and the reeds, dust is excluded from the air-chambers, and the reeds work with greater accuracy of tone. The reeds d have on their base ends plugging projections d', which close, when the reeds are in position as shown in Fig. 1, the openings e, through which the reeds are run into position. A notch (shown in dotted lines) is made in the end of the reed-plates to draw them out with. To tune the reeds it is only necessary to swing or slide the front of the organ-case, when the reeds can be withdrawn one at a time by a hook, and the valve-operating devices do not have to be disturbed or the wind-chest or large chamber O opened.

Reeds d are supported in channels cut in the walls of the air-chambers, as indicated in the drawings. Arrows indicate the direction of the air through the reeds and air-chambers when the air-valves P are opened in the large wind-chest O by means of knee or bell cranks P', rods P'', and metal screw-stem eyes P'', operated from the key-board. The upper reed d, it will be noticed, is reversed from the positions of the other reeds—that is, the tongue side is down, while the reed is arranged in an inclined position. By this arrangement the chamber M is made to qualify the tone, so that a separate qualifying tube or pipe is not re-

quired, although one may be employed, if preferred in any case.

By the construction and relative arrangement of the parts as described tones and action from a reed-organ are obtained equaling if not surpassing those of expensive pipe-organs. A spring-supporting piece, O', is secured to the back of the reed-pan, in which the springs O² are supported, as indicated in the drawings, slots being cut in the supporting-piece to receive the rear arm of the spring.

The front arm, O³, of the spring has at its lower end a bend or forward projection, 8, that enters a hole in the back of the valve P, and said spring by its action keeps its valve to its seat 9 when the rod P² is not depressed.

The valve-seats 9 are recessed, as shown at 10 in the drawings, so that the valve-seat is confined to a narrow line on the outsides of such recesses; consequently the valve fits tight and has but little friction on its seat. The valve is so hung that it can adjust itself under the spring-pressure. Valve P is shown closed in full lines, Fig. 1, and open in dotted lines, same figure. It is suspended perpendicular like a pendulum and hangs on a pin, f. The hole in the upper end of the valve is concaved out, as shown in dotted lines, so that the valve hangs on the inner beveled edge of the wood, and is thus free to swing and adjust itself to its seat. Its face is provided with proper packings, gg', and its lower end works between proper guide-pins, h; consequently the valve when it swings into place closes all the air-induction ports in a very perfect manner, since the mode of suspending and guiding the valve is such as not to bind it laterally.

The upper back side of bell-crank lever P' is padded at j, thereby preventing noise and rendering the action on the screw-stemmed eye P³ easy. By using the eye the latter can be turned to the right or left, and thus secure a perfect center or balance action on the valve by the bell-crank, while at the same time the curved edge of the eye is always acted upon, which reduces friction and secures ease of action. The pad k also prevents noise, and the use of an eye on the upper end of rod P² also secures ease of action. Buffer h' also prevents the valve P from being thrown too far back, and also prevents noise. Rod P² works through a hole in a thin metal piece, l, held in place as shown in the drawings.

Wind-chest O is formed by the back board, Q, fastened to the top and bottom pieces, R and S. It is also provided with proper end pieces.

It will be observed that valve P is so arranged that it opens widest at the ports i which require the most air. Then, again, by the recessed seat the air passes quickly to all the ports i as soon as the valve opens, and to prevent the backing up of air from the three connected air-chambers through a single qualifying-tube cut-offs m are employed, which cut off or close the upper recessed seats from the lower recessed seats, as fully indicated in the drawings, thus guarding against the air from

one of the said connected reed-chambers backing up and causing the reeds in one of the other connected air-chambers to sound prematurely.

I will here state that by the use of a single qualifying tube or pipe for three reeds and their respective air-chambers a large qualifying tube or pipe can be used, and thereby a very deep and heavy tone is obtained for each of said connected reeds—a result which gives to a comparatively small instrument great power and quality.

My reed-organ can be made at a comparatively small expense as compared with pipe-organs of the same tone and capacity.

Having described my improvements in reed-organs, what I claim therein as new and of my invention is—

1. The combination, in a reed-pan of a reed-organ, of the separate tube or cell pieces A, A', C, D, and E, arranged horizontally one above the other, as shown, and extending from front to back and from end to end of the reed-pan, with a series of separate dividing-boards, B', C', and D', arranged horizontally above their respective air-chambers, as shown, and extending from front to back and from end to end of the reed-pan without a break or opening, and all securely fastened together in the relative positions described, and for the purposes stated.

2. The combination and arrangement, in a reed-organ, of a series of air-chambers, A, A', C, D, and E, one above the other in the order named, a series of qualifying-tubes, N, extending horizontally toward the front of the organ and securely fastened to the air-exit ends of the air-chamber pieces, and having communicating ports or openings with their respective air-chambers, but smaller than the qualifying-tubes, and a series of hinged stops, N², at the outer ends of the qualifying-tubes N at the front of the organ, all arranged relatively as described, and for the purposes set forth.

3. The combination, in a reed-organ, with three communicating air-chambers, and a single qualifying tube or pipe and three reeds and the air-chambers above the same, of a stationary cut-off interposed or arranged between air-chambers and reed-chambers above described, and the air-chambers next above the same, substantially as and for the purposes set forth.

4. The combination and relative arrangement, in a reed-organ, of a reed-pan having its induction air-ports and air-valves thereof and mechanism for operating the same located and arranged in the large wind chest or chamber O on the back of the organ or reed pan, in combination with openings for the insertion and removal of the reeds with their respective plugs, located and arranged in the front of the reed-pan and between the horizontal qualifying-tubes, as shown and described, and for the purposes set forth.

5. The combination, in a reed-organ, of a series of reeds and induction air-passages leading

- from a single large air-chest, O, and arranged one above the other, of a single long perpendicular or pendulum air-valve, P, for the whole series, the lowest reed giving the lowest note 5 and its induction air-port opened and closed by the part of the valve having the greatest swing or motion, while the ascending scale of notes is produced by reeds the air-ports of which are closed and opened by the parts of the valve 10c having a gradually-decreasing motion, as and for the purposes set forth.
6. The combination, in a reed-organ, with the perpendicular air-valve P and series of air-induction ports *i*, of recessed seat 9, substantially as described.
7. The combination, with the pendulum-valve P, of pin *f*, guide-pins *h*, operating-spring O², and buffer *h'*, substantially as and for the purposes set forth.
- 20 8. The combination, with the lower end of valve P, of the adjustable screw-stemmed metal eye P³, substantially as and for the purposes set forth.
9. The combination, with valve P, screw-stemmed metal eye P³, padded bell or knee crank P', and rod P², arranged in relation to each other as and for the purposes set forth.
10. The combination, in a reed-organ, of a series of reeds, *d*, arranged one above the 30 other and located in respect to their respective air-chambers as described, with a series of

horizontal qualifying-tubes, N, extending from the ends of the air-chambers toward the front of the organ and arranged one above the other, with open spaces extending in between them from the front of the organ for the passage of the reeds, and with air-exit openings N' and hinged stops N², all relatively arranged as and for the purposes stated.

11. The combination, in a reed-organ, with a series of reed air-chambers, F G H I J K and L M, arranged one above the other, and a series of reeds, *d*, one reed to each set of air-chambers, and inserted therein from the front of the organ and supported in horizontal positions in grooves formed in the sides of the air-chamber pieces, of a series of plug-pieces, B, C', D', and E', arranged and securely fastened on the front side of the reed-pan, and a series of qualifying-tubes, N, secured to the front ends of the air-chambers and extending to the front of the organ, with horizontal open spaces between them for the insertion and removal of the reeds without opening the wind-chest or moving the air-valves or mechanism 55 for operating the same, substantially as shown and described.
